JOHNATHAN R. FREEZE, OF MIDDLETOWN, OHIO, ASSIGNOR TO THE AMERICAN ROLLING MILL COMPANY, OF NEWARK, NEW JERSEY, AND MIDDLETOWN, OHIO.

NESTABLE CULVERT.

1,207,710.

Specification of Letters Patent. Patented Dec. 12, 1916.

Application filed March 8, 1916. Serial No. 82,808.

To whom it may concern:

Be it known that I, JOHNATHAN R. FREEZE, a citizen of the United States, residing at Middletown, Butler county, Ohio, have invented certain new and useful Improvements in Nestable Culverts, of which the following is a specification.

This invention pertains to that class of sheet metal culverts formed of separate sections united to each other on circumferential and longitudinal lines, the sections being originally separate from each other so that they may be nested for storage and shipment, efficient joint devices being provided for securing the sections together.

The present invention will be readily understood from the following description taken in connection with the accompanying drawing in which:

20. Figure 1 is a plan of a culvert built up from nestable sections and uniting devices in exemplification of my present invention.
- 25 Fig. 2 a vertical longitudinal section of the same in the plane of line *a* of Figs. 1, 3 and 4: Fig. 3 an end view of the culvert: Fig. 4, a transverse section of a portion of the culvert in the plane of line *b* of Figs. 1 and 2: and Fig. 5 a longitudinal section of a portion of the culvert at one of the overlapping joints, the section being taken in the plane of line *a* of Figs. 1, 3 and 4.

A diversity of scales is employed in the drawing.

In the drawing:—1, indicates the left rear segmental section of the culvert, the culvert being illustrated in the present instance as being composed of two semi-circular halves: 2, the righthand end of section 1: 3, circumferential corrugations formed in the section 1: 4, the second rear section, similar to section 1, but overlapping it: 5, the lefthand end of section 4: 6, the third rear section, the same overlapping section 4: 7, the lefthand end of section 6: 8, the three sections thus far considered, the same constituting one semi-circular long half of the culvert: 9, the rear half of the culvert, similar to semi-circular half 8, the two halves 8 and 9 having their long edges placed near each other to form a substantially complete circular pipe: 10, longitudinal spaces between the edges of the halves 8 and 9, these spaces being due to the fact that the edges of the two halves are somewhat separated from each other: 11, outwardly projecting

shoulders formed on the longitudinal edges of the sections, these shoulders being preferably formed by striking up the edges of the metal in such manner that the shoulders follow the curves of the hills and valleys of the corrugations, the shoulders being but a short distance from the contiguous edges of the culvert halves: 12, cover-strips disposed inside the culvert, at the longitudinal joints thereof and fitting the circular curvature of the culvert and fitting also the sinusoids of the corrugations of the sections, these cover-strips being formed in sections overlapping each other so as to completely close the interior of the spaces between the edges of the culvert halves: 13, similar cover-strips covering the outside of the spaces between the culvert halves: and 14, bolts passing through the inside and outside cover-strips and through the spaces between the culvert halves, preferably at the crests of the corrugations in the culvert halves and cover-strips.

The individual pipe half-sections are to be preferably uniform in all respects and, as an example, about two feet long, and cover-strips are preferably to be made of the same length, and it is desirable that other cover-strips be provided of somewhat greater length. The inside cover-strips and outside cover-strips are alike in that selected cover-strips may be placed inside or outside the pipe.

Now, taking two of the half-pipe culvert sections which, as stated, may be about two feet long, and placing their edges near each other, and bolting cover-strips at the inside and outside of the joints, and drawing the bolts tightly, a culvert pipe about two feet long is produced. The grip of the cover-strips on the shoulders 11 at the edges of the sections prevents the separation of the sections and produces a strong piece of culvert which is ready for use but which may be disassembled by loosening the bolts, thus permitting the two halves of the pipe to be nested together, and the pairs of culvert-strips to be laid within the nested pipe-halves, thus facilitating storage and shipment. And this nesting may be done with any reasonable number of the pipe-halves and their corresponding pairs of cover-strips.

If a culvert pipe about four feet long is wanted then, in building up the sections and

cover-strips, the contiguous ends of the half pipe are overlapped one corrugation, as indicated in Fig. 5, and the cover-strips are similarly lapped at their contiguous ends, 5 and so on for a culvert pipe of any desired length built up of a longitudinal series of lapping sections and lapping cover-strips. As shown in Fig. 5, one pipe-section laps upon the other to the extent of a single corrugation but if an exact length of total culvert is required then the ends of the sections may overlap to the extent of two or more corrugations, as indicated at the overlapping of the ends 2 and 5 in Fig. 2, and this 10 endwise lapping of sections may be to the extent of any desired number of corrugations to bring out the proper length. And so, also, with the cover-strips, which may lap each other to the extent of one or a 15 greater number of the corrugations. By employing lengths of cover-strips greater than the length of the pipe-sections, the lapping of the cover-strips may be caused to occur at longitudinal points other than those 20 where the pipe sections lap, this being the preferable construction. In other words, desired length of culvert may be secured by varying the overlap of the sections, and the corresponding total length of the cover- 25 strips may be arrived at by lapping them to the extent of the proper number of corrugations, it being obvious that, under the system disclosed, there can, with a sufficient number of culvert half-sections and cover- 30 strips, be built up from nestable parts a culvert of any desired length and having its sections tightly bound together longitudinally and circumferentially. At some given point in the mid-length of the pipe there 35 may be only three thicknesses of metal, represented by the single thickness of culvert-pipe and two thicknesses of cover-strip, while at the lapping points there may be four or more thicknesses of metal as represented by two thicknesses of pipe and two 40 or more thicknesses of cover-strip. The illustration assumes the pipe as being formed of two semi-circular segmental portions joined by two pairs of cover-strips, 45 but it is manifest that the pipe may be made up of more than two segments and involve a correspondingly increased number of joints and cover-strips.

Particular attention should be called to 50 the bolts 14 employed in clamping the cover-strips to the pipe-sections. It is preferred that there be a bolt at each corrugation, and by locating these bolts at the crests of the corrugations and providing the bolts with 55 non-circular heads, the heads of the bolts seat upward in the corrugations and are thereby prevented from turning while the exterior nuts are being turned. The bolts serve not only in drawing the cover-strips 60 together and toward the metal of the pipe-

sections but also in compressing any packing or luting material which may be employed in improving the tightness of the joint. The bolts, in drawing toward each other the cover-strips of a pair, serve also 70 in drawing together the lapping ends of the pipe-sections where they lap more than one corrugation.

The cover-strips being entirely independent of each other before being applied to the pipe-sections, are capable of overlapping or breaking joint with the joints between the ends of the pipe-sections, and of breaking joint between the ends of the cover-strips. In other words, outside cover-strips may 80 break joint with the inside cover-strips and to any extent desired.

I claim:—

1. A nestable culvert comprising a circumferential series of pipe sections, said pipe sections being formed with shoulders near their longitudinal edges, cover-strips adapted to overlap the contiguous edges of said pipe sections and formed with shoulders arranged to engage the shoulders thereon, and means 85 whereby said cover-strips may be secured to said pipe sections to secure the same together, combined substantially as set forth.

2. A nestable culvert comprising, a circumferential series of pipe-sections having 95 their longitudinal edges spaced apart, outwardly presenting shoulders upon the pipe-sections near their longitudinal edges, separable cover-strips disposed outside the joints and overlapping the contiguous edges 100 of the pipe-sections and formed with interior shoulders engaging the shoulders on the pipe-sections, and bolts passing between the contiguous edges of the pipe-sections and through the separable cover-strips and means whereby said bolts are adapted to draw the inner surfaces and shoulders of the cover-strips firmly to the outer surfaces and shoulders of the pipe-sections, combined substantially as set forth.

3. A nestable culvert comprising, a circumferential series of circumferentially corrugated pipe-sections having their longitudinal edges spaced apart, outwardly presenting shoulders upon the pipe-sections near 110 their longitudinal edges, and following the sinusoids of the corrugations, transversely corrugated separable cover-strips disposed outside the joints and overlapping the contiguous edges of the pipe-sections and formed with interior shoulders engaging the shoulders on the pipe-sections, and bolts passing between the contiguous edges of the pipe-sections and through the separable cover-strips and means whereby said bolts 115 are adapted to draw the inner surfaces and shoulders of the cover-strips firmly to the outer surfaces and shoulders of the pipe-sections, combined substantially as set forth.

4. A nestable culvert comprising, a cir- 120

5 circumferential series of pipe-sections having their longitudinal edges spaced apart, outwardly presenting shoulders upon the pipe-sections near their longitudinal edges, sep-
5 arable cover-strips disposed outside and in-
10 side the joints and overlapping the contiguous edges of the pipe-sections and formed with shoulders engaging the shoulders on the pipe-sections, and bolts passing between the contiguous edges of the pipe-sections and

through the separable cover-strips and adapted to draw the surfaces and shoulders of the cover-strips firmly to the surfaces and shoulders of the pipe-sections, combined substantially as set forth.
